CLAIM

The ornamental design of the lid with flat top and captive closure for use with drink bottle, as shown and described.

DESCRIPTION

FIG. 1 is a perspective view taken from the upper, front, right-hand side of the lid with flat top and captive closure for use with drink bottle of the present invention;

FIG. 2 is a perspective view taken from the lower, front, left-hand side of the lid with flat top and captive closure for use with drink bottle of FIG. 1;

FIG. 3 is a front elevational view of the lid with flat top and captive closure for use with drink bottle of FIG. 1;

FIG. 4 is a side elevational view of the right side of the lid with flat top and captive closure for use with drink bottle of FIG. 1; FIG. 5 is a back elevational view of the lid with flat top and captive closure for use with drink bottle of FIG. 1;

FIG. 6 is a side elevational view of the left side of the lid with flat top and captive closure for use with drink bottle of FIG. 1; FIG. 7 is a top plan view of the lid with flat top and captive closure for use with drink bottle of FIG. 1; and,

FIG. 8 is a bottom plan view of the lid with flat top and captive closure for use with drink bottle of FIG. 1.
